ABSTRACT

Box blanks, boxes, and corresponding methods of forming the same are provided. The box blank comprises a plurality of panels and bottom flaps. Each of the plurality of panels and the plurality of bottom flaps are connected along a foldable section score line. The plurality of panels are connected to the plurality of bottom flaps along a panel score line. At least one web pattern score extends in one of the plurality of bottom flaps comprising a first score line and a second score line extending within the bottom flap. A first subsection is defined between the second score line and the section score line, and a second subsection is defined between the first score line and the second score line. The at least one web pattern score enables folding such that the first subsection folds towards the second subsection when the box blank is being formed into the box.

LOCKING BOTTOM BOX BLANKS, BOXES AND METHODS OF FORMING THE SAME

RELATED APPLICATIONS

This application claims priority to U.S. Provisional Application No. 63/449,108, filed on Mar. 1, 2023, which is incorporated by reference herein in its entirety.

FIELD OF THE INVENTION

Example embodiments of the present invention generally relate to paper-based (e.g., corrugate, paperboard, etc.) box designs and corresponding methods of manufacturing and methods of forming the boxes.

BACKGROUND

Box blanks may be formed of a web of material including, corrugate, paperboard, or other materials. The box blank comprises various cuts, cut outs, perforations, scores and/or compressions that aid in folding thereof and/or erecting a box therefrom. A box may be assembled by a user and/or with a box maker (e.g., a case erector).

Various box designs provide benefits depending on their desired usage. Some box blanks are designed to be easily erected by a user, such as prior to packing the newly erected box. For example, some boxes are designed to have a “locking” bottom that is formed when the user erects the box. Such a “locking” bottom may be secure for receiving items therein without additional tape or other securing features being required. Notably, however, current box designs with a “locking” bottom have limited strength for holding items therein. Further, material must be removed from the bottom flaps of the box to enable folding by a user. That material removal creates unnecessary scrap material that is wasteful and can clog various systems during the manufacturing process.

BRIEF SUMMARY

Various embodiments of the present invention are directed to box blanks (and corresponding boxes, methods of manufacturing, and methods of forming the boxes) that are designed to provide a “locking” bottom, where the box design provides improved strength and creates little to no scrap material during manufacturing. Further, erecting of the box by the user requires less time than currently available box designs with a “locking” bottom.

In some embodiments, the box blank may be formed with a die cut positioned on a machine (e.g., a die cutting press). When the die cut pattern requires holes in the box blank, the scrap material resulting from the cut may remain in the die cut or press itself rather than being ejected. The un-ejected scrap material must be manually removed, either from the die or the blank. Further, in addition to assembly and disassembly, any down time to repair or adjust the die cuts (e.g., due to scrap material) may reduce efficiency. Thus, the current “locking” bottom box designs create difficulties for high throughput manufacturing processes because they create too much scrap material.

Moreover, the cutouts of the box blanks of current “locking” bottom box designs reduce the amount of material used to create the bottom structure when the box blank is erected into a box. While the cutouts allow for easy erecting of the bottom structure, they also cause weakness within the bottom structure due to the lack of overlap of material through-

out the structure, which may lead to ruptures of the bottom structure when items are placed therein.

In contrast, various embodiments of the present invention provide box blanks (and corresponding boxes, methods of manufacturing, and methods of forming the boxes) that reduce the amount of scrap material, and still improve the ease of formation and strength of the box. In some embodiments, rather than including multiple cut outs within the box blank, the box blank includes a plurality of scores that are arranged in score lines (which may be referred to as, for example, crease lines, lines of weakness, etc.) and/or cuts arranged so that the box blank is pliable, while not creating scrap material. For example, in some embodiments, one or more web pattern scores are created in one or more of the bottom flaps. The web pattern scores remove the need for cut-outs and enable ease of folding to occur during box erection by the user. Further, the retained material on the bottom, once formed into a box, provides increased strength. Moreover, retaining the material, instead of removing it as scrap, allows for formation of the box blanks in high throughput box manufacturing systems.

In an example embodiment a box blank for a box is provided. The box blank comprises a first section comprising at least a first panel and a first bottom flap connected along a first portion of a panel score line. The box blank further comprises a second section comprising at least a second panel and a second bottom flap connected along a second portion of the panel score line. The first section and the second section being connected along a first section score line. The box blank further comprises a third section comprising at least a third panel and a third bottom flap connected along a third portion of the panel score line. The second section and the third section being connected along a second section score line. The box blank further comprises a fourth section comprising at least a fourth panel and a fourth bottom flap connected along a fourth portion of the panel score line. The third section and the fourth section being connected along a third section score line. The box blank further comprises a flap comprising at least a flap panel and/or a flap bottom connected along a flap portion of the panel score line. The flap is connected to either the first section or the fourth section along a fourth section score line. Each of the panel score line, the first section score line, the second section score line, the third section score line and the fourth section score line are foldable. The panel score line intersects each of the first section score line, the second section score line, the third section score line, and the fourth section score line.

The box blank further comprises at least one web pattern score extending in one of the first bottom flap, the second bottom flap, the third bottom flap, or the fourth bottom flap. The at least one web pattern score comprises a first score line extending a first distance along the one of the first bottom flap, the second bottom flap, the third bottom flap, or the fourth bottom flap. The first score line extends at a first angle away from either one of the first section score line, the second section score line, the third section score line, or the fourth section score line or an intersection of the panel score line and one of the first section score line, second section score line, third section score line or the fourth section score line. The at least one web pattern score further comprises a second score line extending a second distance along one of the first bottom flap, the second bottom flap, the third bottom flap, or the fourth bottom flap. The second score line extends at a second angle away from at least one of: the first score line; one of the first section score line, the second section score line, the third section score line or the fourth section

score line; or the intersection of the panel score line and one of the first section score line, the second section score line, the third section score line, or the fourth section score line. the second angle is less than the first angle such that the first score line and the second score line form a web-like pattern that includes a first subsection between the second score line and one of the first section score line, the second section score line, the third section score line, or the fourth section score line and a second subsection between the first score line and the second score line. The web pattern score enables folding such that the first subsection folds towards the second subsection when the box blank is being formed into the box.

In some embodiments, the at least one web pattern score may be at least a first web pattern score and a second web pattern score. The first web pattern score may extend within the first bottom flap and the second web pattern score may extend within the third bottom flap.

In some embodiments, the at least one web pattern score may further comprise a third web pattern score extending within the fourth bottom flap. In some embodiments, the first score line of the first web pattern score may extend from one of either the intersection of the panel score line and the first section score line or the first section score line. A first score line of the second web pattern score may extend from one of either the intersection of the panel score line and the second section score line or the second section score line. A first score line of the third web pattern score may extend from one of either the intersection of the panel score line and the third section score line or the third section score line.

In some embodiments, the at least one web pattern score may further comprise a fourth web pattern score extending within the fourth bottom flap. A first score line of the fourth web pattern score may extend from one of either the intersection of the panel score line and the fourth section score line or the fourth section score line.

In some embodiments, the box blank may further comprise at least one adjacent face. The at least adjacent face may be on an opposing side if either the first section score line, the second section score line, the third section score line or the fourth section score line than the at least one web pattern score. In some embodiments, the first subsection and the second subsection may be in face-to-face contact with the at least one adjacent face with the box blank is formed into a box.

In some embodiments, the web pattern score may further comprise a hook defined by a through cut extending from the first score line and extending at least partially within the at least one bottom flap. In some embodiments, the hook may extend over at least one of the first section score line, the second section score line, the third section score line, the fourth section score line, the panel score line, or the intersection of the panel score line and one of the first section score line, the second section score line, the third section score line, or the fourth section score line.

In some embodiments, the at least one second score line may extend to an outer edge of one of the first bottom flap, the second bottom flap, the third bottom flap, or the fourth bottom flap. In some embodiments, the box blank may further comprise a tab defined by at least one cut extending partially within one of the first bottom flap, the second bottom flap, the third bottom flap, or the fourth bottom flap. The first score line of the at least one web pattern score may extend to the at least one cut defining the tab.

In some embodiments, the first section may further comprise a first tab defined by at least one cut extending at least partially from an outer edge of the first bottom flap into the

first bottom flap. In some embodiments, the second section may further comprise a receiving tab defined by at least one cut extending at least partially from an outer edge of the second bottom flap into the second bottom flap. In some embodiments, the third section may further comprise a second tab defined by at least one cut extending at least partially from an outer edge of the third bottom flap into the third bottom flap. In some embodiments, the fourth section may further comprise a securing tab defined by at least one cut extending at least partially from an outer edge of the fourth bottom flap into the fourth bottom flap. In some embodiments, the receiving tab may be defined by a first cut and a second cut, and similarly the securing tab may be defined by a first cut and a second cut.

In some embodiments, the first section may further comprise a first top flap connected to the first panel along a first section of a top flap score line. In some embodiments, the second section may further comprise a second top flap connected to the second panel along a second section of the top flap score line. In some embodiments, the third section may further comprise a third top flap connected to the third panel along a third section of the top flap score line. In some embodiments, the fourth section may further comprise a fourth top flap connected to the fourth panel along a fourth section of the top flap score line. In some embodiments, the top flap score line may be foldable.

In some embodiments, the first subsection and the second subsection of the at least one web pattern score may come into proximate or face-to-face contact when the box is being formed into a box. In some embodiments, the first angle may be between the 30-60 degrees. In some embodiments, the second angle may be between 15-25 degrees. In some embodiments, the first distance may be greater than the second distance. In some embodiments, the section score line may comprise a perforated portion and a through cut portion. In some embodiments, the first score line may comprise a first section and a second section. The first section may comprise perforations, and the second section may comprise a through cut. In some embodiments, the second section of the first score line may extend into a hook. In some embodiments, the flap may comprise the flap panel and the flap bottom.

In another example embodiment a method of forming a box is provided. The method comprises providing a blank. The blank comprises a first section comprising at least a first panel and a first bottom flap connected along a first portion of a panel score line. The blank further comprises a second section comprising at least a second panel and a second bottom flap connected along a second portion of the panel score line. The first section and the second section being connected along a first section score line. The blank further comprises a third section comprising at least a third panel and a third bottom flap connected along a third portion of the panel score line. The second section and the third section being connected along a second section score line. The blank further comprises a fourth section comprising at least a fourth panel and a fourth bottom flap connected along a fourth portion of the panel score line. The third section and the fourth section being connected along a third section score line. The blank further comprises a flap comprising at least a flap panel and or a flap bottom connected along a flap portion of the panel score line. The flap is connected to either the first section or the fourth section along a fourth section score line. Each of the panel score line, the first section score line, the second section score line, the third section score line and the fourth section score line are foldable. The pane score

line intersects each of the first section score line, the second section score line, the third section score line, and the fourth section score line.

The blank further comprises at least one web pattern score extending in one of the first bottom flap, the second bottom flap, the third bottom flap, or the fourth bottom flap. The at least one web pattern score comprises a first score line extending a first distance along the one of the first bottom flap, the second bottom flap, the third bottom flap, or the fourth bottom flap. The first score line extends at a first angle away from either one of the first section score line, the second section score line, the third section score line, or the fourth section score line or an intersection of the panel score line and one of the first section score line, second section score line, third section score line or the fourth section score line. The at least one web pattern score further comprises a second score line extending a second distance along one of the first bottom flap, the second bottom flap, the third bottom flap, or the fourth bottom flap. The second score line extends at a second angle away from at least one of: the first score line; one of the first section score line, the second section score line, the third section score line or the fourth section score line; or the intersection of the panel score line and one of the first section score line, the second section score line, the third section score line, or the fourth section score line. the second angle is less than the first angle such that the first score line and the second score line form a web-like pattern that includes a first subsection between the second score line and one of the first section score line, the second section score line, the third section score line, or the fourth section score line and a second subsection between the first score line and the second score line. The web pattern score enables folding such that the first subsection folds towards the second subsection when the box blank is being formed into the box. The method further comprises adhering the flap to the first section to form a four walled structure.

In some embodiments, the method may further comprise folding the second bottom flap towards a center of the four walled structure. The method may further comprise folding the first bottom flap towards the center of the four walled structure, such that a portion of the first bottom flap is in face-to-face contact with the second bottom flap. The method may further comprise folding the third bottom flap towards the center of the four walled structure, such that a portion of the third bottom flap is in face-to-face contact with the second bottom flap. The method may further comprise folding the fourth bottom flap towards the center of the four walled structure, such that a first portion of the fourth bottom flap is in face-to-face contact with the first bottom flap and a second portion of the fourth bottom flap is in face-to-face contact with the third bottom flap. The method may further comprise tucking a tab portion of the fourth bottom flap below a receiving portion of the second bottom flap.

In yet another example embodiment a box formed from a box blank is provided. The box comprises a first section comprising at least a first wall and a first bottom flap connected along a first portion of a panel score line. The box further comprises a second section comprising at least a second wall and a second bottom flap connected along a second portion of the panel score line. The first section and the second section are connected along a first section score line. The box further comprises a third section comprising at least a third wall and a third bottom flap connected along a third portion of the panel score line. The second section and the third section are connected along a second section score line. The box further comprises a fourth section comprising

at least a fourth wall and a fourth bottom flap connected along a fourth portion of the panel score line. The third section and the fourth section are connected along a third section score line. The box further comprises at least one of a flap wall or a flap bottom connected along a flap portion of the panel score line. The flap is connected to either the first section or the fourth section along a fourth section score line. Each of the panel score line, the first section score line, the second section score line, the third section score line, and the fourth section score line are foldable. The panel score line intersects each of the first section score line, the second section score line, the third section score line, and the fourth section score line.

The box further comprises at least one web pattern score 15 extending in one of the first bottom flap, the second bottom flap, the third bottom flap, or the fourth bottom flap. The web pattern score comprises a first score line extending a first distance along the one of the first bottom flap, the second bottom flap, the third bottom flap, or the fourth bottom flap. 20 The first score line extends at a first angle away from either one of the first section score line, the second section score line, the third section score line, or the fourth section score line or an intersection of the panel score line and one of the first section score line, second section score line, third section score line or the fourth section score line. The at least one web pattern score further comprises a second score line extending a second distance along one of the first bottom flap, the second bottom flap, the third bottom flap, or the fourth bottom flap. The second score line extends at a second angle away from at least one of: the first score line; one of the first section score line, the second section score line, the third section score line or the fourth section score line; or the intersection of the panel score line and one of the first section score line, the second section score line, the third section score line, or the fourth section score line. the second angle is less than the first angle such that the first score line and the second score line form a web-like pattern that includes a first subsection between the second score line and one of the first section score line, the second section score line, the third section score line, or the fourth section score line and a second subsection between the first score line and the second score line. The web pattern score enables folding such that the first subsection folds towards the second subsection when the box blank is being formed into the box. 45 Each of the first bottom flap, the second bottom flap, the third bottom flap, and the fourth bottom flap are folded along the panel score line to form a continuous bottom web.

In yet another example embodiment a box blank is provided. The box blank comprises a plurality of panels including at least a first panel, a second panel, a third panel, and a fourth panel. Each of the panels is connected to the adjacent panel at a section score line portion, each section score line portion being foldable. The box blank further comprises a flap extending from either the first panel or the fourth panel. The box blank further comprises a plurality of bottom flaps. The plurality of bottom flaps extend from the plurality of panels along a panel score line. The plurality of bottom flaps define at least one web pattern score. The at least one web pattern score comprises a first score line and a second score line. The plurality of bottom flaps are foldable along the panel score line, utilizing the first score line and the second score line to form a continuous bottom web when the box blank is formed into a box.

In yet another example embodiment a box formed from a box blank is provided. The box comprises a plurality of walls including at least a first wall, a second wall, a third wall, and fourth wall. Each of the walls is connected to an

adjacent wall at a foldable section score line portion. The box further comprises a flap extending from either the first wall or the fourth wall, and the flap is adhered to either the first wall or the fourth wall. The box further comprises a plurality of bottom flaps. The plurality of bottom flaps extend from the plurality of walls along a panel score line. The plurality of bottom flaps define at least one web pattern score comprising a first score line and a second score line. When the plurality of bottom flaps are folded along the panel score line utilizing the first score line and the second score line thereby forming a continuous web bottom. The continuous web bottom extending between and perpendicular to the plurality of walls.

BRIEF DESCRIPTION OF THE SEVERAL VIEWS OF THE DRAWING(S)

Having thus described the invention in general terms, reference will now be made to the accompanying drawings, which are not necessarily drawn to scale, and wherein:

FIG. 1A illustrates an example box blank, in accordance with some embodiments discussed herein;

FIG. 1B illustrates an example section of the box blank shown in FIG. 1A, in accordance with some embodiments discussed herein;

FIG. 2A illustrates an example box blank defining sections, in accordance with some embodiments discussed herein;

FIG. 2B illustrates features of the example box blank shown in FIG. 2A, in accordance with some embodiments discussed herein.

FIGS. 3A-F illustrate various configurations of example web pattern scores, in accordance with some embodiments discussed herein;

FIGS. 4A-F illustrate a perspective view of formation of an example bottom structure of a box, in accordance with some embodiments discussed herein; and

FIG. 5 illustrates a flowchart of an example method of forming a box blank, and forming a box from the box blank, in accordance with some embodiments discussed herein.

DETAILED DESCRIPTION

Some example embodiments now will be described more fully hereinafter with reference to the accompanying drawings, in which some, but not all example embodiments are shown. Indeed, the examples described and pictured herein should not be construed as being limiting as to the scope, applicability or configuration of the present disclosure. Rather, these example embodiments are provided so that this disclosure will satisfy applicable legal requirements. Like reference numerals refer to like elements throughout.

Notably, while some embodiments describe various positional qualifiers for various features, such as “top”, “bottom”, “front”, “back”, “side”, etc. embodiments described herein are not meant to be limited to such qualifiers unless otherwise stated. Directional qualifiers herein are generally used to aid in describing the invention in the context of the drawings and/or description but are not otherwise intended to be limiting.

While some embodiments describe a “user”, use of such a term herein is not meant to be limited to a person or a single person, as the “user” may be an end user, a consumer, a manufacturer, among other types of users along a supply chain in relation to the box design. Further, when utilizing the word “user”, the actor(s) may be operating one or more

machines/system that cause the intended function (e.g., forming the box blank or converting the box blank to a box).

An example box blank 100 is shown in FIG. 1A. With reference to FIGS. 1A-2B, the box blank 100 is formed of a continuous piece of material, the box blank comprising a plurality of panels 110, a plurality of top flaps 120, a plurality of bottom flaps 130 and a flap 119. The box blank 100 may comprise a first outer edge 100a, a second outer edge 100b, a third outer edge 100c, and a fourth outer edge 100d, defining an outer periphery of the box blank 100. In some embodiments, the fourth outer edge 100d may be parallel to the second outer edge 100d and may be perpendicular to both the first outer edge 100a and the third outer edge 100c. In some embodiments, the second outer edge 100b may comprise a plurality of gaps 138 such that in some embodiments the second outer edge 100b may not be continuous. Additionally, in some embodiments, the flap 119 may define a portion of the third outer edge 100c and may not extend from the fourth outer edge 100d to the second outer edge 100b.

Notably, in some embodiments, the box blank 100 may be processed through one or more manufacturing systems at various stages, such as described herein. For example, in some embodiments, the box blank 100 may be formed from a web of corrugated material which may be cut into the box blank 100. Thereafter, the box blank 100 may be further processed through a die cut to form desired cuts, scores, and/or impressions thereon. Further, the box blank 100 may be passed through a box maker to form the box and/or an intermediate state of the box. In other embodiments, the box blank 100 may be formed of paperboard or other materials.

In some embodiments, the box blank 100 may comprise multiple adjacent sections 102, each comprising one of the plurality of panels 110, one of the plurality of top flaps 120 and one of the plurality of bottom flaps 130.

In some embodiments, the plurality of panels 110 correspond to walls of a formed box (corresponding walls can be seen in the box form 200 illustrated in FIGS. 4A-F). In this regard, the term “panels” may be used when in a box blank form and the term “walls” may be used when in the erected/formed box form, although such differentiation in terminology is not required for an understanding of what is being described or claimed. Similarly, the plurality of bottom flaps 130 may correspond to the bottom structure (e.g., corresponding bottom structure 203 can be seen in the box form 200 illustrated in FIGS. 4A-F).

In some embodiments, the plurality of top flaps 120 may be connected to the plurality of panels 110 along a top flap score line 107. In some embodiments, the top flap score line 107 may be continuous between the first outer edge 100a and the third outer edge 100c. In some embodiments, the box blank 100 may be foldable along the top flap score line 107.

In some embodiments, the plurality of panels 110 may be connected to the plurality of bottom flaps 130 along a bottom flap score line 109. The plurality of bottom flaps 130 may be positioned opposite the plurality of top flaps 120. In some embodiments, the bottom flap score line 109 may be continuous between the first outer edge 100a and the third outer edge 100c. In some embodiments, the box blank 100 may be foldable along the bottom flap score line 109.

In some embodiments, a pattern web score 140 may be formed within one of the plurality of bottom flaps 130 and may assist in erecting the plurality of bottom flaps 130 into a bottom of the formed box (e.g., FIG. 4F).

Adjacent sections 102 may be connected via a corresponding section score line 105. In some embodiments, each section score line 105 may be continuous between the

adjacent panels and adjacent bottom flaps. In this regard the section score line 105 may be continuous between the fourth outer edge 100d and the second outer edge 100b, or the gaps 138 when the second outer edge 100b is discontinuous. In some embodiments, the sections 102 of the box blank 100 may be foldable about the section score line 105. As used herein, the term "score" may be used to describe a compression of the internal support system of the blank without creating a cut therethrough, while in other embodiments the term "score" may include a weakness, perforations and/or a cut extending through the blank 100.

In some embodiments, one or more of the plurality of panels 110 may comprise a handle 170 disposed in the body of the panel 110. In some embodiments, the handle 170 may be defined by a through cut along a portion of the handle 170, and an uncut portion. Thus, the handle may be shifted from the plane of the box blank 100 and may be foldable along the uncut portion. In some embodiments, the uncut portion may be a score line, without through cuts. In some embodiments, the handle 170 may be fully scored about the perimeter of the handle. In this regard, the handle may be removed from the box blank 100 after formation of the box. In another embodiment, the handle 170 may be formed of a score line, without a through cut about the perimeter. In such example embodiments more force may be required to remove the handle from the plane of the box blank 100.

FIG. 1B illustrates an example section 102 of the box blank 100. Each section 102 of the box blank comprises one of the plurality of panels 110, one of the plurality of top flaps 120 and one of the pluralities of bottom flaps 130. In some embodiments, each of the plurality of panels 110 comprises a first edge 110a, a second edge 110b, a third edge 110c, and a fourth edge 110d. In some embodiments, the first edge 110a and the third edge 110c are parallel, and the first edge 110a is perpendicular to each of the second edge 110b and the fourth edge 110d. Similarly, each of the plurality of top flaps 120 comprises a first edge 120a, a second edge 120b, a third edge 120c, and a fourth edge 120d. In some embodiments, the first edge 120a and the third edge 120c are parallel, and the first edge 120a is perpendicular to each of the second edge 120b and the fourth edge 120d. Likewise, the plurality of bottom flaps 130 each comprise a first edge 130a, a second edge 130b, a third edge 130c, and a fourth edge 130d and the first edge 130a and the third edge 130c are parallel, while the first edge 130a is perpendicular to each of the second edge 130b and the fourth edge 130d.

As noted above, the box blank 100 and, thus, each section 102 are formed of a continuous piece of material. In this regard, the second edge 110b of the plurality of panels 110 and the fourth edge 120d of the plurality of top flaps 120 are the same edge, and the fourth edge 110d of the plurality of panels 110 and the second edge 130b of the plurality of bottom flaps 130 are the same edge. Said differently, the second edge 110b of the plurality of panels is coextensive with the fourth edge 120d of the plurality of top flaps 120, and the fourth edge 110d of the plurality of panels 110 is coextensive with the second edge 130b of the plurality of bottom flaps 130.

In some embodiments, each of the plurality of panels 110 defines a panel length L_P , wherein the panel length L_P extends between the first edge 110a and the third edge 110c. In some embodiments, the panel length L_P is between 8-20 in, 9-19 in, or 10-18 in. In some embodiments, each of the plurality of panels 110 defines a panel width W_P extending between the second edge 110b and the fourth edge 110d of the panel. In some embodiments, the panel width W_P is between 5-10 in, between 6-9 in, or between 7-8 in. In some

embodiments, each of the plurality of panels 110 defines the same panel width W_P . In some embodiments, each of the plurality of panels 110 defines the same panel length L_P , while in other embodiments the plurality of panels 110 may alternate panel lengths L_P . For example, in an example embodiment, adjacent panels may define different panel lengths L_P , while alternating panels may define the same panel lengths L_P .

In some embodiments, each of the plurality of bottom flaps 130 defines a bottom flap length L_{BF} , wherein the bottom flap length L_{BF} extends between the first edge 130a and the third edge 130c. In some embodiments, the bottom flap length L_{BF} is between 8-20 in, 9-19 in, or 10-18 in. In some embodiments, the bottom flap length L_{BF} is equal to the panel length L_P of the corresponding panel of the plurality of panels 110.

In some embodiments, each of the plurality of bottom flaps 130 defines a bottom flap width W_{BF} , extending between the second edge 130b and the fourth edge 130d. In some embodiments, the bottom flap width W_{BF} is between 3-8 in, between 4-7 in, or between 5-6 in. In some embodiments, each of the plurality of bottom flaps 130 defines an equal bottom flap width W_{BF} , while the bottom flap length L_{BF} changes across the plurality of bottom flaps 130 corresponding to the panel length L_P of the corresponding panel of the plurality of panels 110.

In some embodiments, each of the plurality of top flaps 120 defines a top flap length L_F , wherein the top flap length L_F extends from the first edge 120a to the third edge 120c. In some embodiments, the top flap length L_F is between 8-20 in, 9-19 in, or 10-18 in. In some embodiments, the top flap length L_F is equal to the panel length L_P of the corresponding panel of the plurality of panels 110. In some embodiments, the top flap length L_F is equal to the panel length L_P , while in other embodiments the top flap length L_F is smaller than the panel length L_P . In this regard, the gap 138 between the plurality of top flaps 120 comprises the difference in length between the top flap length L_F and the panel length L_P . In some embodiments, the gap 138 is between $1/32$ - $1/8$ in, more particularly between $1/16$ - $1/8$ in, while in some embodiments, the gap 138 may be negligible.

In some embodiments, each of the plurality of top flaps 120 defines a top flap width W_F , wherein the top flap width W_F extends between the second edge 120b and the fourth edge 120d. In some embodiments, the top flap width W_F is between 3-8 in, between 4-7 in, or between 5-6 in. In some embodiments, the top flap width W_F may be equal for the plurality of top flaps 120, while the top flap length L_F may change across the plurality of top flaps 120 corresponding to the panel length L_P of the corresponding panel of the plurality of panels 110.

In some embodiments, such as illustrated in FIG. 2A, the box blank 100 may comprise a first section 102a, a second section 102b, a third section 102c, and a fourth section 102d, each comprising a panel, a top flap and a bottom flap. In some embodiments, the first section 102a may comprise a first panel 111 connected to a first bottom flap 131 along a first portion of the bottom flap score line 109a, and a first top flap 121 connected to the first panel 111 along a first portion of the flap score line 107a. The first top flap 121 being connected opposite the first bottom flap 131.

The second section 102b may comprise a second panel 112 connected to a second bottom flap 132 along a second portion of the bottom flap score line 109b, and a second top flap 122 connected to the second panel 112 along a second portion of the flap score line 107b. The second top flap 122 being connected opposite the second bottom flap 132. The

11

second section **102b** may be connected to the first section **102a** along a first section score line **105a** extending between at least the first panel **111** and the second panel **112**, and between the first bottom flap **131** and the second bottom flap **132**.

Similarly, the third section **102c** may comprise a third panel **113** connected to a third bottom flap **133** along a third portion of the bottom flap score line **109c**, and a third top flap **123** connected to the third panel **113** along a third portion of the flap score line **107c**. The third top flap **123** being connected opposite the third bottom flap **133**. The third section **102c** may be connected to the second section **102b** along a second section score line **105b** extending between at least the second panel **112** and the third panel **113**, and between the second bottom flap **132** and the third bottom flap **133**.

Additionally, the fourth section **102d** may comprise a fourth panel **114** connected to a fourth bottom flap **134** along a fourth portion of the bottom flap score line **109d**, and a fourth top flap **124** connected to the fourth panel **114** along a fourth portion of the flap score line **107d**. The fourth top flap **124** being connected opposite the fourth bottom flap **134**. The fourth section **102d** may be connected to the third section **102c** along a third section score line **105c** extending between at least the third panel **113** and the fourth panel **114**, and between the third bottom flap **133** and the fourth bottom flap **134**.

The flap **119** may comprise at least one of a flap panel **119a** and/or a flap bottom **119b** connected along a fifth portion of the bottom flap score line **109e**. In some embodiments, the flap **119** may comprise only the flap panel **119a**, while in other embodiments the flap **119** may comprise only the flap bottom **119b**. In some embodiments, the flap **119** may comprise both the flap panel **119a** and the flap bottom **119b**. In some embodiments, the flap **119** may further comprise a flap top extending from the flap panel **119a** opposite the flap bottom **119b**. The flap **119** may be connected to the fourth section **102d** along a fourth section score line **105d** extending between at least the fourth panel **114** and the flap panel **119a**. In some embodiments, the fourth section score line **105d** may further extend between the fourth bottom flap **134** and the flap bottom **119b**. Although illustrated as being attached to the fourth section **102d**, the flap **119** may alternatively be attached to the first section **102a**.

In some embodiments, the section score lines may include different kinds of scores along the length of the section score line **105**. In this regard, each of the section score lines (e.g., **105a**, **105b**, **105c**, **105d**) may include a first portion **106a** extending between the flap score line **107** and the panel score line **109**, and a second portion **106b** extending between the panel score line **109** and the fourth outer edge (e.g., **100d** FIG. 1A). In some embodiments, the first portion **106a** and the second section **106b** may comprise different scores. For example, the first portion **106a** may comprise and internal compression, wherein the internal structure of the blank along the first portion **106a** may be crushed such that the blank is foldable along the first portion **106a**. The second portion **106b** may include perforations and through cuts extending through the thickness of the blank **100**. The score through the section portion **106b** may provide flexibility to the blank while maintaining connectivity of the bottom flaps **130**, thereby imparting strength on the box upon formation from the blank **100**.

The box blank **100** may comprise at least one web pattern score **140**. The at least one web pattern score **140** may extend in at least one of the first bottom flap **131**, the second

12

bottom flap **132**, the third bottom flap **133** or the fourth bottom flap **134**. The web pattern score **140** may enable the plurality of bottom flaps **130** to fold into a bottom structure (e.g., **203** FIG. 4F) while maintaining continuity between each of the sections (e.g., **102** FIG. 1A). To explain, the score patterns in the at least one web pattern score **140** allow the plurality of bottom panels (e.g., **130** FIG. 2A) to fold and form into a bottom structure, while not creating any extended cuts, such that any of the plurality of bottom flaps (e.g., **130** FIG. 1A) may move independently of one another. In this regard, the plurality of bottom flaps **130** may be continuous along the box blank **100** even across the first section score line **105a**, the second section score line **105b**, the third section score line **105c**, and the fourth section score line **105d**.

In some embodiments, such as illustrated in FIG. 2B, the box blank **100** may comprise multiple web pattern scores. In some embodiments, a first web pattern score **140a** may extend within the first bottom flap **131**, a second web pattern score **140b** may extend within the third bottom flap **133**, a third web pattern score **140c** and a fourth web pattern score **140d** may extend within the fourth bottom panel **134**. Each of the web pattern scores **140** may correspond to a receiving face **170** on an opposite side of the corresponding section score line **105**. In this regard, the first web pattern score **140a** may correspond to a first receiving face **170a** on an opposite side of the first section score line **105a**. Thus, the first receiving face **170a** may be within the second bottom flap **132**. Similarly, the second web pattern score **140b** may correspond to a second receiving face **170b** on an opposite side of the second section score line **105b**. Thus, the second receiving face **170b** may also extend within the second bottom flap **132**. The third web pattern score **140c** may correspond to a third receiving face **170c** on an opposite side of the third section score line **105c**. Thus, the third receiving face may extend within the third bottom flap **133**. Finally, the fourth web pattern score **140d** may correspond to a fourth receiving face **170d**. The fourth receiving face **170d** may extend within the first bottom flap **131**. In this regard, when the box blank **100** is formed into a box, the fourth section will be adjacent the first section, via the connection between the flap **119** and the first section **102a**, thus the fourth web pattern score **140d** and the fourth receiving face **170d** may be on opposite sides of the fourth section score **105d** when the box blank **100** is erected into a box (see e.g., **200** FIG. 4F).

In some embodiments, one or more of the plurality of bottom flaps **130** may comprise at least one cut **136** extending within the bottom flap, wherein the at least one cut **136** defines a feature within the bottom flap **130**. For example, in some embodiments, the first bottom flap **131** may comprise the at least one cut **136** defining a first tab **160a**. The at least one cut **136** may define an "L" shape wherein the at least one cut comprises two cuts at a 90 degree angle. The first tab **160a** may be foldable along a score line or foldable section. Although described herein as an "L" it should be understood that the at least one cut **136** may be any configuration which may define a tab, for example, curved, defining a smaller angle, defining a larger angle, or even a single cut at an angle. In some embodiments, the first tab **160a** may be connected on one side to the first bottom flap **131**. In some embodiments, the first tab **160a** may be removed completely from the first bottom flap **131**. Similarly, the third bottom flap **133** may comprise a cut **136** defining a second tab **160b**. In some embodiments, the second tab **160b** may be the same as the first tab **160a**. In this regard, the second tab **160b** may be defined by the cut **136** such that the second tab **160b** is

connected to the third bottom flap 133 on a single side. In some embodiments, the first tab 160a may be a mirror imaged opposite to the second tab 160b so as to, together, form a tab portion of the bottom structure when the box is erected.

In some embodiments, the second bottom flap 132 may comprise multiple cuts 136 defining a receiving tab 175a. In some embodiments, the receiving tab 175a may comprise a first cut 136 on one side and a second cut 136 on a second side. In some embodiments, the first cut 136 and the second cut 136 may be spaced apart from the section score line 105. In some embodiments, the first cut 136 and the second cut 136 may be parallel to the section score line 105, while in other embodiments the first cut 136 and the second cut 136 may extend towards, but not intersect the section score line 105. In this regard, the receiving tab 175a may flex within the plane of the box blank 100 such that a securing tab 175b formed in the fourth bottom flap 134 may be nested under the receiving tab 175a when the box blank is formed into a box. In this regard, the fourth bottom flap 134 may comprise a first cut 136 and a second cut 136 on either side of the securing tab 175b. In some embodiments, the securing tab 175b is configured to engage with the receiving tab 175a to secure the bottom of the box when the box blank 100 is erected into a box 200. In some embodiments, the first and second cuts 136 in the fourth bottom flap 134 encourage and aid in folding of the web pattern score 140, such that the securing tab 175b may be positioned under the receiving tab 175a.

In some embodiments, the first cut 136 and the second cut 136 defining the receiving tab 175a may be shorter than the first cut 136 and the second cut 136 defining the securing tab 175b. In this regard, the receiving tab 175a may be a guide for the securing tab 175b. However, once the securing tab 175b is engaged with the receiving tab 175a the shorter cuts 136 of the receiving tab 175a prevent the securing tab 175b from disengaging without an application of force.

As discussed herein, the at least one web pattern score 140 is configured to aid in the folding of the plurality of bottom flaps 130 into the bottom of the formed box. FIGS. 3A-F illustrate various configurations of the at least one web pattern score 140. In some embodiments, the at least one web pattern score 140 extends within one of the plurality of bottom flaps 130 (e.g., the first bottom flap 131, the second bottom flap 132, the third bottom flap 133, or the fourth bottom flap 134 as shown in FIG. 2A).

In some embodiments, the at least one web pattern score 140 comprises a first score line 141 and a second score line 142. The first score line 141 may extend away from (although it may not be directly connected to) the corresponding section score line 105 (e.g., the first section score line 105a, the second section score line 105b, the third section score line 105c, or the fourth section score line 104d FIG. 2B), illustrated in FIGS. 3A, and 3D-F, or an intersection 155 of the panel score line 109 and the corresponding section score line 105 (e.g., the first section score line 105a, the second section score line 105b, the third section score line 105c, or the fourth section score line 104d FIG. 2B), illustrated in FIGS. 3B-C.

The second score line 142 may extend from one of: the first score line 141, illustrated in FIGS. 3A-B and 3F, the intersection of the panel score line 109 and the respective section score line (e.g., the first section score line 105a, the second section score line 105b, the third section score line 105c, or the fourth section score line 104d FIG. 2B), illustrated in FIG. 3C, or from the section score line (e.g., the first section score line 105a, the second section score line

105b, the third section score line 105c, or the fourth section score line 104d FIG. 2B), illustrated in FIGS. 3D-F. In some embodiments, the second score line 142 may contact the first score line 141, for example, as shown in FIGS. 3A-D, while in other embodiments the second score line 142 may be distinct from the first score line, as illustrated in FIG. 3E. In this regard, the term extend away from may indicate that the score line extends all the way to the point or extends generally from the area around the point.

10 In some embodiments, the first score line 141 extends a first distance D₁ within one of the plurality of bottom flaps 130 (e.g., the first bottom flap 131, the second bottom flap 132, the third bottom flap 133, or the fourth bottom flap 134 FIG. 2A).

15 The first score line 141 may extend at a first angle α₁ in relation to the section score line 105. In some embodiments, the first angle α₁ may be up to 60 degrees, up to 50 degrees, or up to 40 degrees. In some embodiments, the first angle α₁ may be 45 degrees. In some embodiments, the first score line

20 141 may extend to one of the cuts 136 defining one of the first tab 160a, illustrated, the second tab (e.g., 160b FIG. 2B), the receiving tab (e.g., 175a FIG. 2B) or the securing tab (e.g., 175b FIG. 2B). In this regard, extending the first score line 141 to the cut 136 provides the web pattern score 140 with flexibility within the respective bottom flap 130. The flexibility allows the web pattern score 140 to deform to fold into the bottom of the box, and reform into a planar pattern.

25 The second score line 142 may aide in the flexibility of the web pattern score 140 such that the web pattern score 140 may deform and reform into the planar pattern upon formation of the box. Thus, in some embodiments, the second score line 142 may extend a second distance D₂ within the corresponding bottom flap 130. In some embodiments, the first distance D₁ of the first score line 141 may be greater than the second distance D₂ of the second score line 142.

30 The second score line 142 may extend at second angle α₂ in relation to the first score line 141. In this regard, the second angle α₂ is less than the first angle α₁. In some

35 embodiments, the second angle α₂ may be less than 40 degrees, less than 30 degrees, or even less than 20 degrees. In some embodiments, the second angle α₂ may be between 10-40 degrees, between 10-30 degrees, or even between 15-25 degrees. In some embodiments, the second angle α₂ may be 22.5 degrees.

40 The first score line 141 and the second score line 142 may define subsections within the web pattern score 140. In some embodiments, a first subsection 143 may be defined between the section score line 105 (e.g., the first section score line 105a, the second section score line 105b, the third section score line 105c, or the fourth section score line 104d FIG. 2B) and the second score line 142. In some embodiments, a second subsection 144 may be defined between the first score line 141 and the second score line 142.

45 In some embodiments, the first score line 141 and the second score line 142 may be an internal score, wherein the interior side of the blank is compressed. In some embodiments, the first score line 141 and the second score line 142 may comprise a series of perforations configured to impart flexibility on the bottom flap 130 while maintaining connectivity of the bottom flaps 130 as a continuous web.

50 In some embodiments, the web pattern score 140 may comprise a hook 150. In some embodiments, the hook 150 may extend within the respective bottom flap 130, while in other embodiments the hook 150 may extend to the adjacent bottom flap (e.g., across the section score line 105) or into the adjacent panel (e.g., across the panel score line 109). In

55

60

65

15

some embodiments, the hook 150 may be a through cut. The hook feature may aid in flexibility of the bottom flap and web pattern score, such as during deforming of the web pattern score, while limiting the size of cut needed. In some embodiments, the through cut may extend into the first score line 141. Thus, as illustrated in FIG. 3F, a first distance D_4 of the first score line 141 may be a through cut, while a second portion D_3 of the first score line 141 may include perforations thereby providing flexibility to fold the first subsection 143 and the second subsection 144 to form the bottom of the box.

Although described with a first score line 141 and a second score line 142, in other embodiments a third or more score line(s) may be added between either the first score line 141 and the second score line 142, or between the second score line 142 and the section score line 105.

Example Process

FIGS. 4A-F illustrate example formation of the bottom structure of an example box 200 formed from an example blank (e.g., 100 FIG. 1A). In some embodiments, the flap 219 may be attached to the first section (e.g., 102a FIG. 2A) thereby forming a first wall (e.g., 211) and a first bottom flap 231. In some embodiments, the flap 219 may be connected using a glue, an epoxy, an adhesive or similar to secure the blank into a four walled structure 201 as illustrated in FIG. 4A.

The four walled structure 201 may include the first wall, and first bottom flap, a second wall 212 and second bottom flap 232, a third wall 213 and a third bottom flap 233, and a fourth wall (e.g., 214 FIG. 4C) and a fourth bottom flap 234. In some embodiments, each of the walls and bottom flaps are connected along a panel score line 209 that is foldable.

In some embodiments, the bottom flaps are foldable along the panel score line to form the bottom of the box. In some embodiments, a first tab 260a and a second tab 260b are formed within the first bottom flap 231 and the third bottom flap 233 respectively, while in other embodiments a cut in each of the first bottom flap 231 and the third bottom flap 233 may be sufficient.

In regards to the present example, the first tab 260a and the second tab 260b are folded out of the plane of the first bottom flap 231 and the third bottom flap 233 respectively. The movement of the first tab 260a and the second tab 260b provides space and flexibility in the first bottom flap 231 and the third bottom flap 233 to allow the second bottom flap 232 to fold towards the interior of the four walled structure 201, illustrated by arrow 290.

FIG. 4B illustrates an intermediate position of the four walled structure 201 as the second bottom flap 232 is transitioned to form the bottom of the box. The four walled structure 201 comprises at least one web pattern score 240, comprising a first score line 241b and a second score line 242b. The at least one web pattern score 240 defines a first subsection 243 extending between the second score line 242b and the section score line 205, and a second subsection 244 extending between the first score line 241b and the second score line 242b.

As the second bottom flap 232 is transitioned, the third bottom flap 233, (and the first bottom flap 231) fold along the first score line 241, the second score line 242, and the section score line 205. In the intermediate position, in some embodiments, such as illustrated in FIG. 4B, the first subsection 243 and the second subsection 244 are folded together to pass through face-to-face (or near face-to-face)

16

contact on the exterior face, while in other embodiments, for example, shown in FIG. 4D, the first subsection 243 and the second subsection 244 are folded together to pass through face-to-face (or near face-to-face) contact on the interior face.

After the second bottom flap 232 is transitioned towards the interior of the four walled structure 201, as illustrated in FIG. 4C, the first bottom flap 231 and the second bottom flap 233 may be folded towards the middle along the panel score line (e.g., 209 FIG. 4A). A first web pattern score 240a formed in the first bottom flap 231, and a second web pattern score 240b formed in the third bottom flap 233 aid the second bottom flap 232 folding. After the second bottom flap 232 is folded, the first bottom flap 231 and the third bottom flap 233 are folded towards the middle of the four walled structure 201. The first web pattern score 240a is folded onto a first receiving face 270a and the second web pattern score 240b is folded onto a second receiving face 270b each within the second bottom flap 232.

The third web pattern score 240c formed within the fourth bottom panel 234 may deform as described in relation to the at least one web pattern score 240 above to fold the third bottom flap 233 to the center of the four walled structure 201. Similarly, the fourth web pattern score 240d formed within the fourth bottom flap 234 deforms to fold the first bottom flap 231 to the center of the four walled structure 201.

As discussed above, FIG. 4D illustrates configuration of the at least one web pattern score 240c folding. In the illustrated example, the first score line 241c, the second score line 242c, and the section score line 205c are folded to deform the at least one web pattern score 240. In the illustrated example, the first subsection 243 and the second subsection 244 are folded together so the internal portion passes through face-to-face (or near face-to-face) contact.

FIG. 4D further illustrates a hook 250 defining a through cut extending from the first score line 241. The hook 250 is formed such that the first score line 241c does not continue into the walls of the four walled structure 201. This may impart strength onto the bottom of the box as the positioning of the hook 250 may distribute weight positioned in the box across each of the hooks (e.g., corresponding to each of the first web pattern score, second web pattern score, third web pattern score, and fourth web pattern score).

Folding each of the third web pattern score 240c and the fourth web pattern score 240d to allow the first bottom flap 231 and the third bottom flap 233 to be received by the first receiving face 270a and the second receiving face 270b exposes the securing tab 275b.

FIG. 4E illustrates the four walled structure before the fourth bottom flap 234 is folded towards the center of the four walled structure 201. In this regard, the third web pattern score 240c is positioned flush with a third receiving face 270c of the first bottom flap 231, and the fourth web pattern score 240d is positioned flush with the fourth receiving face 270d in the third bottom flap 233.

The securing tab 275b is configured to go under the receiving tab 275a to secure the box bottom together illustrated in FIG. 4F. Thus, a bottom structure 203 comprises the first bottom flap 231, the second bottom flap 232, the third bottom flap 233 and the fourth bottom flap 234 all as a continuous web. In the bottom structure 203 profile, each of the bottom flaps are distinguished by the respective first score line (e.g., 241a, 241b, 241c, 241d).

As mentioned above, the hooks 250 extending from each of the first score lines 241a, 241b, 241c, 241d are oriented in different directions. The difference in the directions of the

hooks **250** provides a positive lock in the bottom structure **203** and improves the strength of the bottom structure. In this regard, the hooks **250** allow for the weight to be distributed along the bottom structure **203** and into the walls when products are placed in the box. In some embodiments, the bottom structure **203** may have an improved strength of over 20% when compared to bottom structures comprising cut outs between each flap (e.g., a discontinuous web). In this regard, in addition to improving the strength of the bottom structure of the box, the die cutting press may produce the box blanks at a greater efficiency by reducing downtime and increasing through put, since there is no scrap material generated by the die cutting press.

Example Flowchart(s)

10

15

Various examples of the operations performed in accordance with some embodiments of the present invention will now be provided with reference to FIG. 5. In this regard, FIG. 5 illustrates a flowchart according to an example method for forming a box from a box blank according to an example embodiment **300**. The operations illustrated in and described with respect to FIG. 5 may, for example, be performed by, with the assistance of, and/or under the control of one or more of a user or a machine for performing the operation (e.g., a corrugator for forming the corrugated box blanks, a die cut for scoring and cutting the corrugated box blanks, a box maker for forming the box or portions thereof, etc.).

Operation **310** may comprise providing a web blank, and operation **320** may comprise running the web blank through a die cutting press to form the box blank with appropriate scores and cuts, such as described herein.

Operation **330** may comprise providing the box blank to a box maker to assemble at least a portion of the box (although box formation may, in some embodiments, occur manually). For example, the box maker may form the box blank into a four walled structure (e.g., connected the flap to a corresponding panel). The resulting four walled structure may then be shipped (e.g., in pallet form or otherwise) to a customer for later box formation and packing.

Then, such as upon arrival at the final destination, operation **340** may comprise erecting the box, such as by forming the bottom structure as described herein. Such a procedure, for example, can be performed manually. Then, at operation **350**, the box may be filled with items, and operation **360** may optionally comprise folding and securing the flaps to secure the box in a closed position. This may be performed using a machine/device and/or via a user.

Conclusion

Many modifications and other embodiments of the inventions set forth herein may come to mind to one skilled in the art to which these inventions pertain having the benefit of the teachings presented in the foregoing descriptions and the associated drawings. Therefore, it is to be understood that the embodiments of the invention are not to be limited to the specific embodiments disclosed and that modifications and other embodiments are intended to be included within the scope of the invention. Moreover, although the foregoing descriptions and the associated drawings describe example embodiments in the context of certain example combinations of elements and/or functions, it should be appreciated that different combinations of elements and/or functions may be provided by alternative embodiments without departing from the scope of the invention. In this regard, for

example, different combinations of elements and/or functions than those explicitly described above are also contemplated within the scope of the invention. Although specific terms are employed herein, they are used in a generic and descriptive sense only and not for purposes of limitation.

What is claimed is:

1. A box blank for a box, the box blank comprising:
  - a first section comprising at least a first panel and a first bottom flap connected along a first portion of a panel score line;
  - a second section comprising at least a second panel and a second bottom flap connected along a second portion of the panel score line, wherein the first section and the second section are connected along a first section score line;
  - a third section comprising at least a third panel and a third bottom flap connected along a third portion of the panel score line, wherein the second section and the third section are connected along a second section score line;
  - a fourth section comprising at least a fourth panel and a fourth bottom flap connected along a fourth portion of the panel score line, wherein the third section and the fourth section are connected along a third section score line;
  - a connecting flap comprising at least one of a connecting flap panel or a connecting flap bottom connected along a flap portion of the panel score line, wherein the flap is connected to either the first section or the fourth section along a fourth section score line;
 wherein each of the panel score line, the first section score line, the second section score line, the third section score line and the fourth section score line are foldable; wherein the panel score line intersects each of the first section score line, the second section score line, the third section score line, and the fourth section score line; and
- at least one web pattern score extending in one of the first bottom flap, the second bottom flap, the third bottom flap, or the fourth bottom flap, wherein the web pattern score comprises:
  - a first score line extending a first distance along the one of the first bottom flap, the second bottom flap, the third bottom flap, or the fourth bottom flap, wherein the first score line extends at a first angle away from either one of the first section score line, the second section score line, the third section score line, or the fourth section score line or an intersection of the panel score line and one of the first section score line, second section score line, third section score line or the fourth section score line; and
  - a second score line extending a second distance along one of the first bottom flap, the second bottom flap, the third bottom flap, or the fourth bottom flap, wherein the second score line extends at a second angle away from at least one of: the first score line; one of the first section score line, the second section score line, the third section score line or the fourth section score line; or the intersection of the panel score line and one of the first section score line, the second section score line, the third section score line, or the fourth section score line, wherein the second angle is less than the first angle such that the first score line and the second score line form a web-like pattern that includes a first subsection between the second score line and one of the first section score line, the second section score line, the third section score line, or the fourth section score line and a

19

second subsection between the first score line and the second score line, wherein the web pattern score enables folding such that the first subsection folds towards the second subsection when the box blank is being formed into the box;

wherein the first bottom flap and the second bottom flap are connected along the first section score line, the second bottom flap and the third bottom flap are connected along the second section score line, and the third bottom flap and the fourth bottom flap are connected along the third section score line, thereby forming a continuous bottom web.

2. The box blank of claim 1, wherein the at least one web pattern score is at least a first web pattern score and a second web pattern score, wherein the first web pattern score extends within the first bottom flap, and the second web pattern score extends within the third bottom flap.

3. The box blank of claim 2, wherein the at least one web pattern score further comprises a third web pattern score, wherein the third web pattern score extends within the fourth bottom flap.

4. The box blank of claim 3, wherein the first score line of the first web pattern score extends from one of either the intersection of the panel score line and the first section score line or the first section score line;

wherein a first score line of the second web pattern score extends from one of either the intersection of the panel score line and the second section score line or the second section score line; and

wherein a first score line of the third web pattern score extends from one of either the intersection of the panel score line and the third section score line or the third section score line.

5. The box blank of claim 4, wherein the at least one web pattern score further comprises a fourth web pattern score, wherein the fourth web pattern score extends within the fourth bottom flap; and

wherein a first score line of the fourth web pattern score extends from one of either the intersection of the panel score line and the fourth section score line or the fourth section score line.

6. The box blank of claim 1, further comprising at least one adjacent face, wherein the at least one adjacent face is on an opposing side of either the first section score line, the second section score line, the third section score line, or the fourth section score line than the at least one web pattern score.

7. The box blank of claim 6, wherein the first subsection and the second subsection are in face-to-face contact with the at least one adjacent face when the box blank is formed into a box.

8. The box blank of claim 1, wherein the web pattern score further comprises a hook defined by a through cut extending from the first score line and extending at least partially within the at least one bottom flap.

9. The box blank of claim 8, wherein the hook extends over at least one of the first section score line, the second section score line, the third section score line, the fourth section score line, the panel score line, or the intersection of the panel score line and one of the first section score line, the second section score line, the third section score line, or the fourth section score line.

10. The box blank of claim 1, wherein the at least one second score line extends to an outer edge of the one of the first bottom flap, the second bottom flap, the third bottom flap, or the fourth bottom flap.

20

11. The box blank of claim 1 further comprising: a tab defined by at least one cut extending partially within the one of the first bottom flap, the second bottom flap, the third bottom flap or the fourth bottom flap, wherein the first score line extends to the at least one cut defining the tab.

12. The box blank of claim 1, wherein the first section further comprises a first tab defined by at least one cut extending at least partially from an outer edge of the first bottom flap into the first bottom flap;

wherein the second section further comprises a receiving tab defined by at least one cut extending at least partially from an outer edge of the second bottom flap into the second bottom flap;

wherein the third section further comprises a second tab defined by at least one cut extending at least partially from an outer edge of the third bottom flap into the third bottom flap; and

wherein the fourth section further comprises a securing tab defined by at least one cut extending at least partially from an outer edge of the fourth bottom flap into the fourth bottom flap.

13. The box blank of claim 1, wherein the first section further comprises a first top flap connected to the first panel along a first section of a top flap score line,

wherein the second section further comprises a second top flap connected to the second panel along a second section of the top flap score line,

wherein the third section further comprises a third top flap connected to the third panel along a third section of the top flap score line,

wherein the fourth section further comprises a fourth top flap connected to the fourth panel along a fourth section of the top flap score line, and

wherein the top flap score line is foldable.

14. The box blank of claim 1, wherein the first subsection and the second subsection of the at least one web pattern score come into or proximate to face-to-face contact when the box blank is being formed into a box.

15. The box blank of claim 1, wherein the first distance is greater than the second distance.

16. The box blank of claim 1, wherein the section score line comprises a perforated portion and a through cut portion.

17. The box blank of claim 1, wherein the first score line comprises a first portion and a second portion, wherein the first portion comprises perforations, and the second portion comprises a through cut.

18. A method of forming a box, the method comprising: providing a blank, the blank comprising:

a first section comprising at least a first panel and a first bottom flap connected along a first portion of a panel score line;

a second section comprising at least a second panel and a second bottom flap connected along a second portion of the panel score line, wherein the first section and the second section are connected along a first section score line;

a third section comprising at least a third panel and a third bottom flap connected along a third portion of the panel score line, wherein the second section and the third section are connected along a second section score line; a fourth section comprising at least a fourth panel and a fourth bottom flap connected along a fourth portion of the panel score line, wherein the third section and the fourth section are connected along a third section score line;

21

a connecting flap comprising at least one of a connecting flap panel or a connecting flap bottom connected along a flap portion of the panel score line, wherein the flap is connected to either the first section or the fourth section along a fourth section score line;

wherein each of the panel score line, the first section score line, the second section score line, the third section score line and the fourth section score line are foldable; wherein the panel score line intersects each of the first section score line, the second section score line, the third section score line, and the fourth section score line; and

10 at least one web pattern score extending in one of the first bottom flap, the second bottom flap, the third bottom flap, or the fourth bottom flap, wherein the web pattern score comprises:

15 a first score line extending a first distance along the one of the first bottom flap, the second bottom flap, the third bottom flap, or the fourth bottom flap, wherein the first score line extends at a first angle away from either one of the first section score line, the second section score line, the third section score line, or the fourth section score line or an intersection of the panel score line and one of the first section score line, 20 second section score line, third section score line or the fourth section score line; and

25 a second score line extending a second distance along one of the first bottom flap, the second bottom flap, the third bottom flap, or the fourth bottom flap, wherein the second score line extends at a second angle away from either: the first score line; one of the first section score line, the second section score line, the third section score line or the fourth sections score line; or the intersection of the panel score line and one of the first section score line, the second section score line, the third section score line, or the fourth section score line, wherein the second angle is less than the first angle such that the first score line and the second score line form a web-like pattern that includes a first subsection between the second score line and one of the first section score line, the second section score line, the third section score line, or the fourth section score line and a second subsection between the first score line and the second score line, where in the web pattern score enables folding such that the first subsection lies adjacent and flush with the second subsection when the box blank is 30 formed into the box; and

35 adhering the flap to the first section to form a four walled structure;

40 wherein the first bottom flap and the second bottom flap are connected along the first section score line, the second bottom flap and the third bottom flap are connected along the second section score line, and the third bottom flap and the fourth bottom flap are connected along the third section score line, thereby forming a continuous bottom web.

45 19. The method of claim 18, further comprising:
folding the second bottom flap towards a center of the four walled structure;
folding the first bottom flap towards the center of the four walled structure such that a portion of the first bottom flap is in face-to-face contact with the second bottom flap;

22

folding the third bottom flap towards the center of the four walled structure, such that a portion of the third bottom flap is in face-to-face contact with the second bottom flap;

5 folding the fourth bottom flap towards the center of the four walled structure, such that a first portion of the fourth bottom flap is in face-to-face contact with the first bottom flap, and a second portion of the fourth bottom flap is in face-to-face contact with the third bottom flap; and

tucking a tab portion of the fourth bottom flap below a receiving portion of the second bottom flap.

20 20. A box formed from a box blank, the box comprising: a first section comprising at least a first wall and a first bottom flap connected along a first portion of a panel score line; a second section comprising at least a second wall and a second bottom flap connected along a second portion of the panel score line, wherein the first section and the second section are connected along a first section score line;

a third section comprising at least a third wall and a third bottom flap connected along a third portion of the panel score line, wherein the second section and the third section are connected along a second section score line; a fourth section comprising at least a fourth wall and a fourth bottom flap connected along a fourth portion of the panel score line, wherein the third section and the fourth section are connected along a third section score line;

30 at least one of a connecting flap wall or a connecting flap bottom connected along a flap portion of the panel score line, wherein the flap is connected to either the first section or the fourth section along a fourth section score line;

35 wherein each of the panel score line, the first section score line, the second section score line, the third section score line, and the fourth section score line are foldable; wherein the panel score line intersects each of the first section score line, the second section score line, the third section score line, and the fourth section score line; and

40 at least one web pattern score extending in one of the first bottom flap, the second bottom flap, the third bottom flap, or the fourth bottom flap, wherein the web pattern score comprises:

45 a first score line extending a first distance along the one of the first bottom flap, the second bottom flap, the third bottom flap, or the fourth bottom flap, wherein the first score line extends at a first angle away from either one of the first section score line, the second section score line, the third section score line, or the fourth section score line or an intersection of the panel score line and one of the first section score line, second section score line, third section score line or the fourth section score line; and

50 a second score line extending a second distance along one of the first bottom flap, the second bottom flap, the third bottom flap, or the fourth bottom flap, wherein the second score line extends at a second angle away from at least one of: the first score line; one of the first section score line, the second section score line, the third section score line or the fourth section score line; or the intersection of the panel score line and one of the first section score line, the second section score line, the third section score line, or the fourth section score line, wherein the second

23

angle is less than the first angle such that the first score line and the second score line form a web-like pattern that includes a first subsection between the second score line and one of the first section score line, the second section score line, the third section score line, or the fourth section score line and a second subsection between the first score line and the second score line, wherein the web pattern score enables folding such that the first subsection folds towards the second subsection when the box blank is 10 being formed into the box,

wherein each of the first bottom flap, the second bottom flap, the third bottom flap, and the fourth bottom flap are folded along the panel score line to form a bottom web, wherein the bottom web is continuous; and 15 wherein the at least one second score line extends to an outer edge of the one of the first bottom flap, the second bottom flap, the third bottom flap, or the fourth bottom flap.

21. A box blank for a box, the box blank comprising: 20 a first section comprising at least a first panel and a first bottom flap connected along a first portion of a panel score line;

a second section comprising at least a second panel and a second bottom flap connected along a second portion of the panel score line, wherein the first section and the second section are connected along a first section score line;

a third section comprising at least a third panel and a third bottom flap connected along a third portion of the panel score line, wherein the second section and the third section are connected along a second section score line;

a fourth section comprising at least a fourth panel and a fourth bottom flap connected along a fourth portion of the panel score line, wherein the third section and the fourth section are connected along a third section score line;

a connecting flap comprising at least one of a connecting flap panel or a connecting flap bottom connected along a flap portion of the panel score line, wherein the flap is connected to either the first section or the fourth section along a fourth section score line;

wherein each of the panel score line, the first section score line, the second section score line, the third section score line and the fourth section score line are foldable; 45 wherein the panel score line intersects each of the first section score line, the second section score line, the third section score line, and the fourth section score line; and

at least one web pattern score extending in one of the first bottom flap, the second bottom flap, the third bottom flap, or the fourth bottom flap, wherein the web pattern score comprises:

a first score line extending a first distance along the one of the first bottom flap, the second bottom flap, the third bottom flap, or the fourth bottom flap, wherein the first score line extends at a first angle away from either one of the first section score line, the second section score line, the third section score line, or the fourth section score line or an intersection of the panel score line and one of the first section score line, second section score line, third section score line or the fourth section score line;

a second score line extending a second distance along one of the first bottom flap, the second bottom flap, 65 the third bottom flap, or the fourth bottom flap, wherein the second score line extends at a second

5

24

angle away from at least one of: the first score line; one of the first section score line, the second section score line, the third section score line or the fourth section score line; or the intersection of the panel score line and one of the first section score line, the second section score line, the third section score line, or the fourth section score line, wherein the second angle is less than the first angle such that the first score line and the second score line form a web-like pattern that includes a first subsection between the second score line and one of the first section score line, the second section score line, the third section score line, or the fourth section score line and a second subsection between the first score line and the second score line, wherein the web pattern score enables folding such that the first subsection folds towards the second subsection when the box blank is being formed into the box; and

a tab defined by at least one cut extending partially within the one of the first bottom flap, the second bottom flap, the third bottom flap or the fourth bottom flap, wherein the first score line extends to the at least one cut defining the tab.

22. A box blank for a box, the box blank comprising: 20 a first section comprising at least a first panel and a first bottom flap connected along a first portion of a panel score line;

a second section comprising at least a second panel and a second bottom flap connected along a second portion of the panel score line, wherein the first section and the second section are connected along a first section score line;

a third section comprising at least a third panel and a third bottom flap connected along a third portion of the panel score line, wherein the second section and the third section are connected along a second section score line;

a fourth section comprising at least a fourth panel and a fourth bottom flap connected along a fourth portion of the panel score line, wherein the third section and the fourth section are connected along a third section score line;

a connecting flap comprising at least one of a connecting flap panel or a connecting flap bottom connected along a flap portion of the panel score line, wherein the flap is connected to either the first section or the fourth section along a fourth section score line;

wherein each of the panel score line, the first section score line, the second section score line, the third section score line and the fourth section score line are foldable; wherein the panel score line intersects each of the first section score line, the second section score line, the third section score line, and the fourth section score line; and

at least one web pattern score extending in one of the first bottom flap, the second bottom flap, the third bottom flap, or the fourth bottom flap, wherein the web pattern score comprises:

a first score line extending a first distance along the one of the first bottom flap, the second bottom flap, the third bottom flap, or the fourth bottom flap, wherein the first score line extends at a first angle away from either one of the first section score line, the second section score line, the third section score line, or the fourth section score line or an intersection of the panel score line and one of the first section score line, second section score line, third section score line or the fourth section score line;

a second score line extending a second distance along one of the first bottom flap, the second bottom flap, the third bottom flap, or the fourth bottom flap, wherein the second score line extends at a second angle away from at least one of: the first score line; 5 one of the first section score line, the second section score line, the third section score line or the fourth section score line; or the intersection of the panel score line and one of the first section score line, the second section score line, the third section score line, 10 or the fourth section score line, wherein the second angle is less than the first angle such that the first score line and the second score line form a web-like pattern that includes a first subsection between the second score line and one of the first section score 15 line, the second section score line, the third section score line, or the fourth section score line and a second subsection between the first score line and the second score line, wherein the web pattern score enables folding such that the first subsection folds 20 towards the second subsection when the box blank is being formed into the box; and wherein the web pattern score further comprises a hook 25 defined by a through cut extending from the first score line and extending at least partially within the at least one bottom flap.

* * * * *
